DECORATIVE DISC FOR KNOBS

Robert J. Malcolm, 311 E. Rockwell,
Arlington Heights, Ill.

Filed Feb. 7, 1963, Ser. No. 73,482

Term of patent 3½ years

(Cl. D10—8)

Fig. 1

Fig. 2

FIG. 1 is a top elevational view of a decorative disc embodying my new design; and

FIG. 2 is a side elevational view of the decorative disc.

The other side views of the decorative disc are the same in appearance as the elevational view shown in FIG. 2, and the bottom of the disc illustrated in FIG. 1 is devoid of ornamentation.

I claim:

The ornamental design for a decorative disc for knobs, substantially as shown and described.
